Primary Examiner — Rosemary K Tarcza(74) *Attorney, Agent, or Firm* — Nitin Kaushik(57) **CLAIM**

We claim the ornamental design for a 2-in-1 wireless charging stand, substantially as shown and described.

DESCRIPTION

FIG. 1 is a top, front and right side perspective view of a 2-in-1 wireless charging stand, showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines in the drawings illustrate the portions of the 2-in-1 wireless charging stand, which form no part of the claimed design.
